UNITED STATES PATENT OFFICE

110,468

DESIGN FOR A ROAD MARKER

Abraham Sprung, New York, N. Y., assignor to
United States Reflector Corp., New York, N. Y.

Application May 29, 1937, Serial No. 69,623

Term of patent 14 years

To all whom it may concern:

Be it known that I, Abraham Sprung, a citizen of the United States, residing in New York city, Queens County, and State of New York, have invented a new, original, and ornamental Design for a Road Marker, of which the following is a specification, reference being had to the accompanying drawing, forming a part thereof.

Fig. 1 is a perspective view of a road marker, showing my new design.

Fig. 2 is a front view thereof.

Fig. 3 is a side view.

I claim:

The ornamental design for a road marker, as shown.

ABRAHAM SPRUNG.
